CLAIM

The ornamental design for a flotation shirt with inflation components, as shown and described.

DESCRIPTION

FIG. 1 is a front elevation view of a flotation shirt with inflation components showing my new design; FIG. 2 is a side elevation view as seen from the right of FIG. 1;

FIG. 3 is a rear elevation view thereof; FIG. 4 is a side elevation view as seen from the left of FIG. 1;

FIG. 5 is a front perspective view thereof;

FIG. 6 is a rear perspective view thereof; and,

FIG. 7 is a top plan view thereof.

The broken lines shown in the figures depict portions of the flotation shirt with inflation components that form no part of the claimed design.
